UNITED STATES PATENT OFFICE.

EDWIN S. LENOX, OF WORCESTER, MASSACHUSETTS, ASSIGNOR TO THE
WASHBURN & MOEN MANUFACTURING COMPANY, OF SAME PLACE.

WIRE-ROD-ROLLING MILL.

SPECIFICATION forming part of Letters Patent No. 351,836, dated November 2, 1886.

Application filed April 9, 1885. Serial No. 161,637. (No model.)

To all whom it may concern:

Be it known that I, EDWIN S. LENOX, a citizen of the United States, residing at Worcester, in the county of Worcester and State of Massachusetts, have invented certain new and useful Improvements in Apparatus for Rolling Wire Rods; and I declare the following to be a description of my said invention, sufficiently full, clear, and exact to enable others skilled in the art to which it appertains to make and use the same, reference being had to the accompanying drawings, which form a part of this specification.

The object of my present invention is to provide an apparatus for rolling wire rods of small size, that can be economically constructed and operated, and that will facilitate the rapid production and convenient working of the rods; also, in a compound rod-rolling apparatus; to provide a single supplementary set or finishing train of rolls having rolls and guides which are adapted for simultaneously carrying through two or more rods, so that the double feeding of said supplemental train can be effected to accommodate the product that passes through the primary train without too rapid revolution of the finishing-rolls or too slow revolution of the primary rolls; also, to afford facilities for the proper guiding of the rods from the primary train to the respective grooves of the finishing-rolls, and for taking care of the over feed of the rods, which occurs intermediately of the respective trains or series of rolls; also, to afford means for the convenient adjustment of the mechanism to bring the guides and either of the several grooves of the rolls into proper working alignment, as may be required; also, to provide a system of overhanging rolls for rod-rolling mills and a double guiding mechanism for use in combination with the reducing-rolls, whereby two or more separate rods can be conducted through separate grooves of said rolls. These objects I attain by mechanism, the nature, construction, and operation of which is illustrated in the accompanying drawings, and explained in the following description, the particular subject-matter claimed being hereinafter definitely specified.

In the drawings, Figure 1 is a plan view of so much of a wire-rod-rolling mill as will illustrate the nature of my invention. Fig. 2 is a front view of the supplemental train on a larger scale. Fig. 3 is a transverse vertical section of the supplemental train at line *x* *x*. Fig. 4 is a transverse vertical section of the over-feed tables at line *y* *y*, Fig. 1. Fig. 5 is a plan view of the device for shifting the supporting-housings for adjusting the rolls to different positions in relation to the delivery-guides. Fig. 6 is a plan view of the double guides. Fig. 7 is a vertical longitudinal section of the same. Fig. 8 is a transverse vertical section of the same. Fig. 9 is a transverse section of the table and guide at line *z* *z*, showing the delivery-mouth of said guide.

In reference to parts, A denotes the primary train of rolls, which may consist of fourteen pairs of rolls (more or less) mounted and operated in the manner of an ordinary continuous rolling-mill, and through which the bar or billet, as taken from the heating-furnace, (also of ordinary or any suitable construction,) is passed and reduced to a rod about of No. 6 wire-gage (more or less) as it is delivered from the last pair of rolls *a* in such primary train.

At the foot of the primary train I arrange a table or platform, B, for the distribution of the over-feed of the rods, and at the foot of said table I locate a single supplemental train of rolls, C, for the further reduction and finishing of the rods, as more fully hereinafter explained. The distributing platform or table is made with a downward lateral inclination at the right and left of the center, which is in line with the working-faces of the two trains of rolls A and C, and along the upper part of said table I arrange a double parallel guideway or conducting-trough, D, having a central upright partition or thin dividing-plate, *d*, adapted for separating rods that are delivered to the right and left sides of said partition from the last pair *a* of the primary train of rolls. The guideway D is adapted for directing the end of the rod as it issues from the rolls *a* across the table into the bite of the leading pair of rolls *c* of the supplemental train C,

and said double guideway extends along the ridge or top of the inclined table in a direct line, as shown.

The guideway or conductor is preferably made laterally adjustable upon the table for the whole or a portion of its length, so that it can be placed, for directing the rod, in conjunction with either of several grooves formed in the rolls, so that when one set of such grooves becomes worn out the work can be brought on to another set of grooves with equal facility. The lower end of the guideway is contracted to a form that will insure the ends of the rods entering properly to the particular groove intended on to the rolls *c*. The partition at the upper end of the double conductor *D* may be made flexible or movable at *f*, so that it can be shifted to receive the rod issuing from rolls *a* at either its right or left side, as desired. This result might otherwise be accomplished by the use of a switching-guide located between said rolls *a* and the end of the partition.

The conductor *D* may be secured to the table *B* by means of bolts passing through slotted ears, as at *e*, and a screw, *E*, and hand-wheel *E'* may be combined therewith, as indicated, for facilitating its lateral adjustment with ease and accuracy when the bolts are slightly loosened.

The main portion of the guideway *D* is open at the top, so that the over-feed of the rod or the surplus delivered from the rolls *a* in excess of the speed at which it is taken in by the rolls *c* can loop out and distribute itself laterally upon the platform *B*, the rods passing at the right of the partition *d* going to the right incline of the platform, and rods passing at the left of said partition going to the left incline of the platform. The incline of the table or platform *B* laterally permits the gravity or weight of the rod to act in assisting its distribution over the surface, and to obviate tangling of the loops as they are drawn in by the rolls of the supplemental train.

Vertical guide-rolls *G* are arranged at the mouth of the funnel or contracted portion *D'* of the guideways to avoid friction on the angles of the guideway, or to prevent the rod from being drawn out of proper position.

The supplemental series of rolls *C* may consist of five pairs of rolls, more or less. These rolls are mounted on the overhanging ends of a series of shafts, *H*, the journals of which are supported, preferably, in a compound housing-frame, *I*, that carries the entire series, and which frame is laterally adjustable upon the main or bed frame.

The gear-shafts *H'* are supported in journal-bearings, the standards *K* of which rest upon the bed-frame *J*, and said gear-shafts are provided with sleeves *H''* that give connection with the roll-shafts *H*, and also permit the longitudinal extension or contraction necessary as the housing-frame is moved forward or back when adjusting the rolls to proper alignment.

The housing-frame is mounted on guideways *J*, and is provided with a shaft, *i*, and worm *i'*, which works in connection with toothed racks *J'*, for effecting the adjustment of said housing-frame and rolls, as desired, by the shaft *i* and worm *i'*, being revolved by means of a suitable wrench or crank placed on the projecting squared end of said shaft *i*.

The worm and shaft *i i'* may be mounted in connection with the housing-frame *I* and the racks attached to the bed-frame *J*, or vice versa, as preferred, the action and effect being the same in either case.

The faces of the rolls *c c' c'' c''' c''''* are each provided with as many forming-grooves as the width of the roll will conveniently admit. The lateral spacings of said grooves and the width of the delivery-passages at the end of the parallel guideway *D* are arranged to coincide in such manner that when said guideway is in position for delivering a rod from one of its channels into one groove of the roll *c* or its leader-guide the other channel will be in correct position for delivering a rod into another one of the grooves of said roll *c* or its leader-guide, so that two separate rods can be fed from said double intermediate guideway, *D*, to the supplemental train of rolls *C*.

The guides *m*, for directing the rods from one pair of rolls to another in the supplemental train, are made double, with two parallel channels, *m'*, as indicated in Figs. 6, 7, and 8. In the present instance the bottom piece of the guide is formed single and the caps in separate parts for each channel. The channels are made to coincide with grooves on the rolls, and are twisted in section throughout their length for turning the rod in the usual manner to give different angular actions at each pair of rolls. The guide-supporting standards *M* are in the present instance mounted on guideways on a projecting ledge, *M*, or laterally-extending portion of the housing-frame *I*, said guide-standards being laterally adjustable and provided with a screw, *n*, which is journaled in the frame and fitted with a screw-thread to the lower part of the guide-standard, so that by turning said screw the standard *M* and guides *m* can be moved forward or back laterally and in relation with the rolls, to bring the channels of the guides accurately into line with the grooves of the rolls.

If preferred, the guide-standards can be mounted in similar manner on a portion of the bed-frame *J*, instead of upon the housing-frame. Instead of making each guide-standard separately adjustable, the entire series, or any number of standards, may be connected to a single foot or bearing plate, so that they would all move together.

The forms of grooves provided in the several rolls may be such as are usually employed for imparting the desired sectional shape to the rod at its several stages of reduction, the final pair of rolls having grooves of the size and form to be imparted to the finished rod.

In the operation of my improved apparatus the heated billets or bars from the furnace are passed through the primary train A in the manner ordinarily practiced in a continuous 5 rolling-mill. The end of the rod as it issues from between the rolls a passes into the guideway D, at one side of the partition d, (say, at the right,) and runs along said guide to the supplementary frame, where it is directed by 10 the contracted end of said guideway D², in such manner that it shoots into one of the grooves in the bite of the first pair of rolls c, and from thence through the several guides and rolls of the finishing-series. As it is my object to 15 avoid too high a rate of speed for the final pair of rolls, and yet not be compelled to run the leading roll of the primary train too slow, the speed of the rolls c may be made less than the speed of the rolls a. Hence there would 20 occur a greater or less percentage of over-feed of the rod between the two trains, and this is accommodated by the inclined table B. The rod loops out laterally over the side of the guideway upon the platform or table, and the 25 inclination of the surface of said table allows the loops of the rod, by their gravity, to slide down the surface and to expand to the full extent required, and in a manner to be readily drawn in by the rolls in due time.

30 The advantages attained by making the table or platform inclined are that the loops of the rod can be extended more readily, while the inclination tends to keep the loops of the rods in condition to be drawn through the secondary train with greater facility and with 35 less liability of forming kinks or tangles in the rods when the over-feed is rapidly drawn off from the platform by said secondary train. The first rod having passed through 40 the primary train, a second bar is without delay inserted in said train, the end of the partition or switch is shifted so that the end of said second rod takes the guideway D at the left of said partition, and passing to the supplemental train before the latter portion of 45 the first rod has been drawn through, its end enters one of the other grooves in the bite of the pair of rolls c, and, in order passes, forward through the train, the two rods being simultaneously 50 carried and worked by the double guides m and the respective pairs of rolls of which said supplementary train is composed. In like manner rods from the primary train are passed down the double parallel guideway 55 alternately at the right and left of the partition d, so that the single supplementary train, while it is run at a practical speed, is enabled, by reason of its working upon two rods simultaneously, to take care of the product as it 60 comes from the primary train; and this, too, without the necessity of slowing down the rolls of the primary train, or without requiring the reheating of the rods at an intermediate stage of the rolling operation.

65 The inclined table or platform B, with the double parallel guideway D, arranged as herein described, may be employed in connection

with a rolling-mill or single supplemental train in which the rolls are mounted, in other manner than as herein shown, and in some cases 70 I so intend to use said inclined table and the guide devices D.

In some instances, or, if desired, the double parallel guideways may be permanently fixed to the inclined platform B; but I prefer to 75 have it laterally adjustable thereon, either throughout its entire length, or for a convenient portion of its length, at the end, so as to change it for feeding at different grooves of the rolls.

As the finished wire rods issue from the 80 final rolls of the supplemental train, they may be led by suitable guides to separate reeling mechanism, R R', which reels may be made to wind up the rods by automatic action, or in any other suitable manner desired. As I do 85 not include claims to such reeling mechanism as a part of my present invention, I have not shown the devices in detail herein.

In cases where it would be inconvenient to make the entire housing-frame I in a single 90 casting or piece, owing to its size or the extent of the train, said frame may be made in two or more sections, each section being arranged and adjusted substantially as the single frame herein shown.

95 What I claim as my invention, and desire to secure by Letters Patent, is—

1. In an apparatus for rolling wire rods, the combination of a primary train of rolls, a double inclined platform or overfeed table, 100 double parallel guideways, and a single supplemental or finishing train, the rolls of which are provided with a plurality of grooves, substantially as and for the purpose set forth.

2. In a wire-rod-rolling mill, a laterally-inclined table or platform for receiving the over-feed of the rod, located intermediately between series of reducing-rolls.

3. The combination, with a series of rod-reducing rolls, of a rod-conducting guide having a dividing partition, and a set of finishing-rolls adapted for simultaneously passing separate rods, substantially as and for the purpose set forth.

4. The combination, with a primary series 115 of reducing-rolls and a secondary series of rolls, of an intermediately-located guideway having a dividing partition, and a contracted delivery-mouth adapted for leading two wire rods from the primary train and directing 120 them into separate grooves of the following rolls or the supplementary train, substantially as set forth.

5. In an apparatus for making wire rods, the combination, with the reducing-rolls a, of a 125 guide or conductor having a dividing partition, one end of which partition is made flexible and laterally movable, whereby it is adapted for adjustment to act at either side of the rod issuing the rolls for directing said rods to the 130 right or left of said partition, substantially as set forth.

6. An apparatus for making wire rods comprising a primary series of rolls in which the

- rod is carried singly, a secondary or finishing train of rolls having a plurality of grooves, intermediate parallel guideways, and inclined tables for receiving the overfeed of the rods, 5 said apparatus being constructed and arranged so that the end of a second rod may be led into the finishing-train before the latter portion of the first or preceding rod has passed from between rolls of said finishing-train.
- 10 7. The combination, with a primary train of reducing-rolls, a supplemental or finishing train of rolls, and an intermediately-located double-inclined overfeed table, of a double parallel guideway or conductor laterally adjustable in relation to said table and the line of rolls, for the purpose set forth.
8. In combination with the rolls of the supplemental train, the housing-frame constructed, substantially as described, for supporting 15 the journals of the several pairs or sets of rolls throughout the series, the same being bodily adjustable laterally, whereby the series can be simultaneously moved to the right or left, as and for the purpose set forth.
- 20

9. The combination, with laterally-adjustable roll-supporting housings and the stationary bed-frame in a rolling-mill, of the shaft i i' , and the toothed racks J^2 , arranged in the manner shown for effecting the adjustment of said housings, as set forth. 25

10. In a continuous wire-rolling mill, the combination, with reducing-rolls having a plurality of wire-forming grooves, of directing-guides m , adapted to carry two separate rods simultaneously, passing through said rolls and 35 guides, substantially as set forth.

11. The combination, with the rolls in a wire-rolling mill, of the guide-standards M , laterally adjustable on their bed or supporting frame, and the screw-shafts n , for effecting 40 adjustment thereof, as set forth.

Witness my hand this 3d day of April, A. D. 1885.

EDWIN S. LENOX.
